UNITED STATES PATENT OFFICE.

EMIL LINDERME, OF PHILADELPHIA, PENNSYLVANIA.

BOTTLE-WASHING MACHINE.

1,104,994.

Specification of Letters Patent. Patented July 28, 1914.

Application filed March 10, 1913. Serial No. 753,212.

To all whom it may concern:

Be it known that I, EMIL LINDERME, a citizen of the United States of America, residing at Philadelphia, in the county of 5 Philadelphia and State of Pennsylvania, have invented certain new and useful Improvements in Bottle-Washing Machines, of which the following is a specification.

The invention relates to machines for 10 cleaning bottles, jars, and similar articles; and it consists generally of the novel construction and arrangement of the several parts, and their specific combination, as will be hereinafter described in this specification, and briefly stated in the claims.

The chief object of the invention is to simplify and cheapen the cost of production of this class of machines without impairing their effectiveness in operation.

20 Other objects of the invention will become apparent upon a complete disclosure thereof.

In the drawings, Figure 1 is a front elevation of my improved bottle-washer, Fig. 2, a horizontal sectional view taken on line 25 2-2 Fig. 1, Fig. 3 is a central vertical section, some of the parts being shown in full lines.

Referring to the several views, the numeral 1 indicates the base provided with 30 suitable supports 2, 3, and 4, in which the drive-shaft 5 is suitably journaled, the supports 2 and 3 being integral in one casting. The shaft is provided with the usual band pulleys, one of which is loose on the shaft.

35 Connected with the support 2-3, by a web, is a support 7 which is provided with an aperture 8 through which passes the internal brush carrying tubular shaft 9, surrounded, for a greater portion of its length, 40 by a sleeve 10 provided at its upper end with a bottle or jar support 11, in which is contained a flexible seat 12, preferably rubber, to receive the mouth of the bottle or jar. The brush-carrying shaft is provided 45 at its lower end with a beveled gear wheel 13 which is in mesh with a similar gear-wheel 14 mounted on the drive-shaft 5. The bottle supporting sleeve is provided at its lower end with a cross-bar 15 having extensions 50 16 to each of which is attached one end of a cord or chain 17, the other end of each cord or chain passing over a pulley 18, secured to the underside of the support 6, and provided with a counter-balance weight 55 19. The bottle supporting sleeve is also provided with a cross-bar 20, which serves

as a stop to limit the upward movement of said sleeve, the two bars being connected together by rods 21, 21.

Journaled in suitable bearings in supports 60 3 and 6 is a shaft 22, provided at its lower end with a beveled gear-wheel 23 in mesh with a similar gear wheel 24 mounted on the drive-shaft 5, and at its upper end with a pinion 25 in mesh with a gear-wheel 26 65 loosely mounted on the bottle supporting sleeve.

Situated below the gear-wheel 26 is a circular rack-bar 27, which is secured in position to the support 6 by screws or bolt 28, as 70 shown in Fig. 3. Passing through the gear-wheel 26, near its periphery, is a brush-shaft 29, and secured to the lower end of said shaft is a pinion 30 which meshes with and travels around said rack-bar as the gear-wheel 26 revolves. Also carried by the gear-wheel 26 is a brush-shaft 31, the two brushes being adapted to clean the outer surface of the bottle or jar, the brush-shaft 29 receiving a rotation independent of the rotation 75 received by the gear-wheel 26, the upper end of the brush-shaft 29 being loosely journaled in a cross-bar 32 which connects the two shafts, 29 and 31, together.

Journaled on a stud-bolt 33, screwed into 80 the support 3, is a gear-wheel 34 in mesh with a pinion 35 mounted on the drive-shaft 5. Eccentrically secured to the gear-wheel 34 is a jointed pitman 36, the free end of which is operative through arms 37, 37 of a 85 bracket 38 slideable on a shaft 39 secured to the support 6 and being provided with an adjustable collar 36' between the pivoted joint and its upper end to engage the lower-most arm 37, on the upper stroke of the pitman to lift part 41, a collar 40 being adjustable on said shaft 39 to limit the downward movement of the bracket. The bracket is provided with an arm 41, the outer end of which is provided with a slideable rod 42 90 carrying at its lower end a rubber clamp 43 adapted to engage the bottom of the bottle, the rod being held in adjusted position by screw 44. The upper end of the pitman is provided with a collar 45, between which 95 and the arm 37 is a coil spring 46 which serves to keep the arm 41, and clamp-rod 42 pressed downwardly with a yielding pressure. The supports 2 and 3 are provided with suitable oiling ducts 47, and the support 4 with a suitable screw-threaded aperture 48 to receive an oil-cup, not shown.

In the operation of the machine described the shaft 5 is driven by a belt (not shown) which passes over the pulleys on said shaft, the pinion 35 rotates the gear 34 causing the pitman which is eccentrically mounted on said gear to move upward, on the upward movement of said pitman the collar 36 engages the lower arm 37 of the bracket 38 raising the arm 41 on bracket 38 and the clamp arm 42 a distance sufficient to allow a bottle to be placed upon its seat in the bottle support. The spring 46 serves to keep arm 41 and clamp 42 pressed downwardly with a yielding pressure. Beveled gear 14 rotates the hollow brush carrying shaft 9 over the upper end of which the bottle is placed, and beveled gear 24 rotates shaft 22 the upper end of which is provided with pinion 25 meshing with gear 26 loosely mounted on the bottle support to revolve the brushes around the bottle to be cleaned. The pinion mounted upon the lower end of brush shaft 29 which passes through gear 26 meshes with a circular rack secured to support 6 causing the brush shaft to rotate upon its axis during the rotation of gear 26. During the cleansing operation water is supplied to the interior of the bottle, the interior brush revolved and the outer brushes are given a movement around the bottle and one of them a planetary movement. It will be obvious that any suitable means may be employed to supply a stream of water through the tubular shaft 9 to the interior of the bottle.

Having thus fully described my invention what I claim is—

1. A bottle cleaner having in combination, a base, upright supports, a drive shaft, a counter-balanced bottle support, a rotatable shaft provided with a pinion at its upper

end, a hollow rotatable shaft carrying an internal brush and having a gear wheel loosely mounted thereon, a series of brushes mounted on said gear, the shaft of one of the brushes extending through said gear and provided with a pinion, a circular rack with which said pinion meshes, whereby a rotary movement is imparted to one of said brushes during the revolution of the brushes around the bottle, an adjustably supported bracket carrying an arm, an adjustable bottle clamping rod mounted in said arm, and means for creating a yielding pressure upon the arm carrying the clamp rod.

2. A bottle cleaner having, in combination, a counter-balanced bottle support, a rotatable brush for cleaning the interior surface of the bottle, a drive shaft, means for rotating the brush, a gear wheel, a jointed pitman pivotally attached to said gear wheel, an adjustably supported bracket having an inwardly extending arm carrying a clamp rod adjustably slidable therein, and outwardly extending arms provided with openings through which the pitman operates, an adjustable collar below the lower outwardly extending arm, a collar on the upper extremity of said pitman, and a spring surrounding the pitman between the uppermost extending arm and collar for creating a yielding pressure upon the arm carrying the clamping rod.

In testimony whereof I have hereunto set my hand in presence of two subscribing witnesses.

EMIL LINDERME.

Witnesses:

ERNEST LINDERME,
THEO. H. McCALLA.
